UNITED STATES PATENT OFFICE.

CHARLES W. DIXON, OF RACINE, WISCONSIN.

LOW-GASOLINE SIGNAL.

Application filed December 20, 1921. Serial No. 523,861.

To all whom it may concern:

Be it known that I, CHARLES W. DIXON, a citizen of the United States, and resident of Racine, in the county of Racine and State of Wisconsin, have invented certain new and useful Improvements in Low-Gasoline Signals; and I do hereby declare that the following is a full, clear, and exact description thereof.

10 The invention is a device operated when the supply of gasoline in the tank of an automobile has decreased to a predetermined point to signal to the operator. It may be used in gravity feed systems or in connection 15 with a vacuum feed.

In the invention, a gasoline feed pipe leads from the gasoline tank as does also an air pipe. A valve is used in connection with the air pipe operable on the lowering of a 20 float supported by gasoline in the tank to admit air to the air pipe, and cause the closure of a ball valve, thus making an electric contact and signalling to the operator by means of a bulb conveniently located on the 25 dash-board.

In one modification of the invention, a 30 vacuum tank is used as a means of creating suction and actuating the ball valve to closed position and also drawing the liquid from the tank.

An object of the modification of the device used in a gravity feed system is the creation of a permanent signal operated when the gasoline has reached a predetermined 35 depth.

An object of the vacuum feed modification is the throwing on of a signal at the decrease of the gasoline supply to a predetermined point. In this case, the operation of 40 the signal is intermittent corresponding with the creation of suction and the cessation thereof in the vacuum tank.

An important feature of both modifications is the provision of a float which is accurately adjustable to operate at any desired depth of gasoline.

A further object is the location of the circuit closing contacts at a point remote from the gasoline tank and, in fact, from all gasoline so as to eliminate all possibility of an explosion resulting from the electric contact.

Other important objects and advantages will appear as the description proceeds.

Reference is had to the accompanying 55 drawing, in which

Figure 1 is a side elevation of the invention.

Figure 2 is a side elevation of the modification wherein a vacuum tank is used. 60

Figure 3 is a cross section of the ball valve, and

Figure 4 is a cross section of the float valve.

Figure 5 is a cross section of a modification 65 of the signalling means.

The structure shown in Figures 3 and 4 appear in both the modification where the 70 vacuum tank is used and that in which it is not used.

The same reference character indicates the same part throughout the figures.

In Figure 1, pipe 11 communicates with carbureter 10 and with gasoline tank 12 for feeding gasoline to the carbureter. Pipe 14 75

connects with the manifold 13 and has threaded thereon, T 15 into one end of which is threaded a connection 16 on pipe 17, which pipe is grounded electrically at 18 and connected to closure 19 by means of an internally threaded cap 20 which is screwed tightly upon nipple 21 integral with closure 19. Closure 19 is threaded internally and in connection with pipe 22 and 80 23.

Closure 19 has a constriction at 24 with 85 which valve 25 contacts for preventing air from entering pipe 17 through vent 26 which is downwardly directed to prevent the entrance of water and may be provided with a screen to eliminate possibility of the entrance of dust. Rod 27 is rigid with valve 25 and provided with a float 28 adjustable thereon by means of screw 29 threaded into sleeve 30 enveloping rod 27. Guides 31 and 32 are provided for guiding rod 27 and preventing looseness of parts and oscillation of float 28.

It is apparent that float 28 will be lowered on the falling of the surface of the gasoline to a predetermined point and thereby move valve 25 to permit air to enter pipe 17 through vent 26.

T 15 is provided with a constriction 33 providing a valve seat for ball 34 which has limited vertical movement resting in its lowermost position on connection 16, as shown in Figure 1, and in its elevated position, as shown in Figure 3. T 15 has a nipple 35, in which an extension 36 of insulation 37

70

80

85

95

105

is threaded, the insulation being threaded internally and receiving collar 38 integral with metallic post 39 with which contacts spring 40, exerting pressure on head 41 rigid 5 with contact pin 42 guided in an aperture in extension 36 and contacting with ball 34 in its elevated position. Post 39 is connected with wire 43 provided with electric bulb 44 and battery 45 grounded at 46.

10 It is apparent that movement of ball 34 into its elevated position wherein it contacts both with T 15 and pin 42 closes an electric circuit and operates to illuminate the bulb.

15 The operation of the device, shown in Figure 1, is therefore as follows:

The proper adjustment of float 28 is made, corresponding to any desired depth of the gasoline. On a lowering of the supply to a 20 predetermined point, float 28 falls, moving rod 27 and valve 25. A sufficient suction occurs in manifold 13 to exercise a lifting action through pipe 14 on ball 34, the removal of valve 25 permitting the entry of 25 air through vent 26, which enables the vacuum to operate.

When ball 34 is in the elevated position shown in Figure 3, it makes contact with pin 42, illuminating bulb 44, as already described. The illuminated condition of the bulb remains continuous as long as the gasoline supply is low.

When gasoline is poured into the tank, valve 25 is restored to its elevated position. 35 In the meantime, because of the cessation of the suction, the ball 34 drops and breaks electric contact with pin 42, thus extinguishing the light. When valve 25 is in its closed position because of the rise of the gasoline 40 in the tank, the relation of parts is such as to permit the operation of the device in the cycle already described, float 28 lowering with the outflow of gasoline.

In the modification shown in Figure 2, a 45 pipe 11' communicates with vacuum tank 50, from which connection 51 leads to the manifold in the manner in which pipe 14 in Figure 1 leads thereto, and connection 52 extends to the carburetor.

50 In this modification, gasoline is being fed through pipe 11'. The fall of float 28 permits entrance of air through vent 26 and the suction created by vacuum tank 50 operates through pipe 14' to lift ball 34, the operation of which is as already described.

In this modification of the device, however, the creation of a vacuum and the cessation thereof in vacuum tank 50, produces an intermittent closing of the circuit and an 60 intermittent rise and fall of ball 34 so that when the gasoline supply becomes low, intermittent illumination of bulb 44 results.

It will be noted that operation of ball 34 65 will not prevent the outflow of gasoline through pipe 11 to vacuum tank 50, as the

ball 34 in its uppermost position prevents the entrance of air into pipe 14' and there is no breaking of the vacuum in vacuum tank 50. When valve 25 moves downwardly, air is sucked thru vent 26 and lifts 70 ball 34 to the position shown in Figure 3.

It is apparent that the location of electrical contacts and apparatus is remote from the gasoline tank and the electricity cannot in any way cause an ignition of the gasoline. 75

I do not limit my signalling device to the specific one shown. If desired, the circuit may be broken on a decrease of the supply instead of closed. This may be done by merely inverting T 15 and the arrangement 80 may be such as to break the entire lighting circuit of the automobile.

In the modification shown in Figure 5, a hollow indicator member 60 has integral nipples 61 and 62 extending therefrom received in holes in the dash 63. A valve member 64 has a channel therein communicating with duct 65 in the indicator and its end is enveloped by a cylindrical observation glass 66 visible to the operator through hole 67. 90 Plug 68, threaded in the indicator member 60, holds glass 66 in position and is channeled at 69 so that air may pass through pipe 17, lift ball 70 and raise it to valve closing 95 position shown. When the ball rises the operator is signalled that the supply of fuel is low. Nut 71 secures plug 68 in position.

While a preferred embodiment of the invention has been illustrated and described, 100 it is to be understood that the present invention is not confined to such specific embodiment, but may be otherwise embodied within the spirit of the invention and the scope of the following claims, and it will further be understood that a substantial 105 range of equivalence is contemplated.

I claim:

1. The combination of a fuel tank, a float controlled by the level of the fuel within said tank, a reduced pressure chamber, a 110 removable member closely fitting said chamber and cooperating with one end of said chamber to seal said chamber against the flow of air and a valve controlled by said float and adapted to admit air to said chamber, whereby when said valve opens said member will be moved and will prevent further flow of air through said chamber. 115

2. The combination of a fuel tank, a float 120 therein, a vertical chamber, a ball located within said chamber and closely fitting such chamber, means for permitting a suction at the upper end of such chamber and a valve controlled by said float and controlling the admission of air to the lower part of said chamber, whereby when said valve is opened by said float said ball will be moved to the upper portion of said chamber. 125

3. In a fuel supply system having an internal combustion engine, the combination of 130

a fuel tank, a vacuum tank permanently connected therewith, a float positioned within said fuel tank, a tube having a constricted end connected with said vacuum tank and 5 a valve controlled by said float and controlling the admission of air to the other end of said tube, whereby when air is admitted to said tube said member will move to the constricted end of said tube and prevent further 10 flow of air therethrough.

4. The combination of means for producing a suction, a transparent tube having one

end connected thereto, a movable member closely fitting said tube, a fuel supply tank, and means controlled by the level of fuel 15 in said tank for admitting air to the other end of said tube, whereby when air is admitted to said tube said member will move towards the first mentioned end of said tube.

In testimony that I claim the foregoing 20 I have hereunto set my hand at Milwaukee, in the county of Milwaukee and State of Wisconsin.

CHARLES W. DIXON.
